UNITED STATES PATENT OFFICE.

WILLIAM F. RITTER, OF CINCINNATI, OHIO.

INCANDESCENT-LAMP SOCKET.

No. 893,873.

Specification of Letters Patent.

Patented July 21, 1908.

Application filed May 13, 1907. Serial No. 373,425.

To all whom it may concern:

Be it known that I, WILLIAM F. RITTER, a citizen of the United States of America, and a resident of Cincinnati, in the county of 5 Hamilton and State of Ohio, have invented certain new and useful Improvements in Incandescent-Lamp Sockets, of which the following is a specification.

This invention relates to an improvement 10 in incandescent electric-lamp sockets, and its object is to relieve the bared ends of the suspension electric feed-wires of any tensile or other strain and to supply a thorough insulator lining and barrier within the dome 15 of said socket in which the lower divergent ends of said lamp wires house and pass to the lamp-terminals.

The invention consists in the provision in connection with an incandescent electric- 20 lamp socket, of a lining made of fiber or other suitable insulating material, such lining being shaped so that its body portion conforms to the interior of the dome portion of said socket and its central portion being 25 extended downward to form a transverse partition with a perforation in said body portion at either side of said partition, whereby the lower divergent ends of the untwisted portion of the lamp-cord are permitted to 30 pass downward and then knotted on the interior of the lining, with a knot at either side of said pendent partition and with the extreme lower ends of said divergent wires duly 35 bared of insulation for proper connection with the terminals of the lamp-socket.

In the accompanying drawings, Figure 1 is a transverse section taken on the dotted-line *b, b*, of Fig. 2, of the cap portion of a lamp-socket containing my improved insulator- 40 lining and showing a fragmentary portion of the lamp-socket shell and, also, the two lamp-cords duly knotted in accordance with the plan and purpose of my invention herein; Fig. 2, a bottom sectional plan taken on the 45 dotted-line *a, a* of Fig. 1 showing the socket-cap, my improved insulator-lining therefor and my improved manner of knotting the lower ends of the lamp-wires within said lining; Fig. 3, a diagram of a piece of insulator material, showing it as it appears prior 50 to being bent and shaped into the form seen in Fig. 1; Fig. 4, a plan view of the blank shown in Fig. 3, but with the next step taken in its process of bending or shaping, such bending being taken on the parallel dotted-lines seen in Fig. 3; Fig. 5, a bottom plan

view of the insulator-lining, in its finished state; and Fig. 6, a side elevation of the insulator-lining as it appears when fully shaped.

In these views, 1 represents the upper portion of the customary metal shell of a lamp-socket; 2, the metal cap, of dome-shape and telescoping the upper end of said shell for suitable attachment thereto; 3, the usual hollow boss or metal protuberance on the 60 cap 2; and 4, the usual insulator-bushing in the protuberance 3.

5 represents a lining of fiber or other suitable insulating material placed within the dome of the cap 2 and preferably shaped to 70 conform to the inner face of said dome. This lining is composed of a strip of material cut into the blank form seen in Fig. 3, with the **V**-shape indentations 6, 6 at either side thereof, the opposite ends 7, 7 being semicircular 75 and with two perforations 8, 8 made therein at a suitable distance apart from the center of the blank. A central pendent extension, forming a partition 9, is made in the blank, the bends in the blank, to produce such partition, being made on the three parallel dotted-lines 10, seen in said Fig. 3 and the outer walls 11, 11 of the lining are produced by concaving the semicircular ends 7, 7 of the blank 80 so as to properly fit within the cap 2 as best 85 seen in Fig. 1. The material comprising the lining is made pliable between the two semicircular concaved ends so that the bends may be readily made therein for producing the partition 9, and the whole is readily inserted into place within the cap 2 so that the holes or perforations 8, 8 approach, with a space between them, just below the orifice or passageway of the bushing 4, as best seen 90 in Fig. 1. The partition 9 serves as a ready 95 means of handling the lining to and from place in the dome of the cap 2.

The lamp-cord composed of the two insulated wires 12, 12 as customary, passes downward through the insulator-bushing 4 and 100 with the divergent lower ends extending downward through the holes 8, 8 in the lining 5, single knots 13, 13 being made in each of said divergent ends so that such knots bear against the inner face of the lining and, also, 105 against the opposite sides of the transverse partition 9, and with the extreme lower ends of such divergent ends passing downward and duly bared or stripped of insulation for proper connection with the lamp-terminals. 110

It will be seen that the lining 5 duly insulates the lamp-cords from the metal cap 2

and the central partition 9 duly insulates the two knots 13, 13 from each other, such partition also separating said knots from each other to prevent abrasion, or rubbing or bearing contact with each other. The weight of the lamp and its supporting-socket is entirely on the knots 13, 13 made in the cords, so that there is no tension whatever on the bared connecting ends of the wires with the lamp-
 10 terminals, thus preventing any undue separation of said bared ends from the lamp-termi-
 nals and any consequent sparking or short-circuiting within the lamp-socket device. The knots 13 are readily made in the cords
 15 and, being single ones, do not occupy material room or space within the upper chamber, such as might be the case if the central partition 9 were omitted and a single knot made in the twisted double cord that would then pass
 20 through but a single central hole in the lining.

I claim:—

1. In a device of the character described, a lining composed of insulator material with its outer walls shaped to correspond to the dome 25 of said device and having a central, pendent transverse partition with a hole or perfora-

tion at either side said partition for the passage of the separated lamp-cords.

2. In a device of the character described, the combination with a dome-cap of an interior insulator-lining, such lining having a transverse central partition made therein and a perforation at either side of said partition, and lamp-cords, each having a single knot made therein and each passing through one 35 of said perforations in the lining.

3. In a device of the character described, a socket-cap lining composed of a blank of insulator material, such blank having semi-circular opposite end-sections, V-shape in-
 40 indentations at either side and intermediate said end sections and two perforations made therein a suitable distance apart at either side the center of the blank, such blank be-
 ing adapted to be folded along three parallel 45 lines to form a central transverse partition in the blank when shaped for use in said device.

WILLIAM F. RITTER.
